FRICITION DEVICES FOR STENOGRAPHIC
TYPEWRITER PLATENS

Harrison M. Von Duyke, Wilmington, Del., assignor to New Dictatype Company, Incorporated, Wilmington, Del., a corporation of Delaware

Application October 28, 1947, Serial No. 782,473

2 Claims. (Cl. 197—138)

1

This invention relates to friction devices for stenographic typewriter platens, that is to say, to devices adapted to be used in connection with the paper feed of stenographic typewriters, for the purpose of enhancing the frictional engagement between the paper and the platen, whereby the paper will be fed uniformly as the platen rotates with a step by step motion during the operation of the machine.

Heretofore, in typewriters, both of the ordinary type and the stenographic type, various devices have been used for the purpose of enhancing the frictional engagement between the paper and the platen, for the purpose of insuring the proper feed of the paper when the platen is rotated. Such devices customarily comprise small rubber rolls, variously located to impel the paper against the surface of the platen to cause the same to be fed in unison with the step by step rotation of the platen.

However, when such devices are made of rubber or the like, they become hardened in the course of time and fail to function properly.

Furthermore, in typewriters of the stenographic type, in which the platen is usually much shorter than in the ordinary typewriters, it is more difficult to provide a satisfactory device of this character, which will be sure and positive in its action, and which will not wear or deteriorate in the course of time.

Also, in stenographic typewriters, the paper is usually provided in strips, folded in what is known as "a fan fold," so that variations in the gripping action occur as the paper is fed over the platen, particularly where the creases occur.

The principal object of the present invention is to provide improved means, particularly adaptable for use in stenographic typewriters, for enhancing the frictional engagement between the paper and the platen.

A further object of the invention is to provide, in a machine of the character aforesaid, a device which will at all times maintain the proper frictional engagement between the platen and paper, notwithstanding irregularities which occur due to the difference in paper thicknesses and when the creases in the paper strip pass over the platen.

A further object of the invention is to provide, in a machine of the character aforesaid, a device which continues to function and will not deteriorate in the course of time, notwithstanding the fact that the peripheral travel of the paper over the platens of the stenographic typewriters is considerably more than that in the ordinary typewriters.

The nature and characteristic features of the present invention will be more readily understood from the following description, taken in connection with the accompanying drawing forming part hereof, in which:

5 Figure 1 is a perspective view of a device embodying the main features of the present invention, the same being shown in connection with the platen of a stenographic typewriter;

10 Fig. 2 is a vertical central section thereof; and Fig. 3 is a top or plan view of the principal portion of the device detached.

15 It should, of course, be understood that the description and drawing herein are illustrative merely, and that various modifications and changes may be made in the structure disclosed without departing from the spirit of the invention.

20 Referring to the drawing, there is therein shown the side plates 5 of the frame of a stenographic typewriter, in which plates a platen 6 is journaled by means of a shaft 7.

25 The friction enhancing device of the present invention comprises principally two metallic rollers 8, preferably spaced circumferentially with respect to the platen 6. Each of the rollers 8 is provided with a plurality of grooves 9, whereby there results a series of relatively narrow spaced peripheral bearing surfaces 10 on each roller.

30 The rollers 8 are each journaled on a transverse shaft 11. The shafts 11 are supported in a suitable frame 12 comprising two side plates 13 and a spacing bar 14 extending therebetween.

35 The side plates 13 of the frame 12 are pivotally mounted on a transverse rod 15. The frame 12, and rollers 8 carried thereby, are positioned intermediate the ends of the platen 6 by means of split washers 16, which engage suitably located grooves 17 in the rod 15.

40 The lower marginal edge 13^a of each of the side plates 13 of the frame 12 is complementary in shape to the surface of the platen 6, and these edges 13^a are spaced a slight distance from said surface so that the side plates 13 of the frame 12 not only serve to support the rollers 8, but also act as guides for the front edge of the paper when the same is being initially fed therethrough.

45 The transverse rod 15 is mounted, at each end, with a more or less loose connection, on the free end of a link 18. Each link 18 is pivotally mounted on one of the side plates 5 of the frame work of the machine by means of a pin 19.

50 On each side of the machine there is provided a coil spring 20, one end of which is connected to

one end of the transverse rod 15, and the other end of which is connected to an arm 21. The arm 21 is secured to the side plate 5 of the machine in such manner that the tension of the coil spring 20 may be varied by shifting the arm 21 to various positions.

The pivotal connections of the links 18 to the side plates 5 of the frame work of the machine are so located with respect to the axis of the platen, and the coil springs 20 are so positioned, that the grooved rollers 8 will be pulled forwardly by the springs 20 with a wedge like action so that a proper and sufficient pressure will be exerted on the paper passing over the platen 6 without unduly stressing the springs 20.

By the foregoing arrangement there is provided a device for enhancing the frictional engagement between the paper and the platen of a typewriter, which is particularly adaptable for use on stenographic typewriters, which will be durable and efficient, and which will readily adjust itself to such variations as occur from time to time, and particularly when the creases in the paper pass over the platen.

The connections between the transverse rod which supports the friction rollers and the spring controlled arms upon which the ends of the transverse rod are mounted are preferably of a loose character so that the friction rollers may readily adjust themselves to such irregularities as occur in the operation of the machine.

I claim:

1. In a typewriter having a platen over which the paper passes during the operation of the machine, means for enhancing the frictional engagement of the paper with the platen comprising a pair of grooved metallic rollers bearing against and spaced circumferentially with respect

to the platen, a frame work carrying said rollers, a transverse rod upon which said frame work is pivotally mounted, links in which said transverse rod is loosely mounted at the ends thereof, and a coil spring on each side of the machine for impelling said rod forwardly, each of said coil springs being connected at one end to one end of said rod and at the other end to the frame work of the machine.

2. In a typewriter having a platen over which the paper passes during the operation of the machine, means for enhancing the frictional engagement of the paper with the platen comprising a pair of grooved metallic rollers bearing against and spaced circumferentially with respect to the platen, a frame work carrying said rollers, a transverse rod upon which said frame work is pivotally mounted, links for supporting said transverse rod at the ends thereof, and a coil spring on each side of the machine for impelling said rod forwardly, said links being pivotally secured to the frame work of the machine below and to the rear of the axis of the platen, and each of the coil springs being connected at one end to one end of said rod and at the other end to the frame work of the machine.
